MACHINE FOR WORKING CEMENT
CONCRETE

Corwill Jackson, Chicago, Ill.

Application August 16, 1930, Serial No. 475,774

8 Claims. (Cl. 25—1)

The main objects of this invention are:

First, to provide a machine for working and finishing concrete in the laying of floors, pavements, gutters, conduits, drains or the like.

Second, to provide a machine for working cement concrete which greatly facilitates the placing of concrete and permits the use of relatively dry concrete mixtures.

Third, to provide a machine of this character which enables the very rapid placing of the concrete with a minimum of labor.

Objects pertaining to details and economies of my invention will definitely appear from the detailed description to follow. The invention is defined in the claims.

A structure which embodies the features of my invention is clearly illustrated in the accompanying drawings, in which:

Fig. 1 is a front elevation of my concrete working machine in operative relation to a form and a bed of concrete, the parts being shown in surface finishing position.

Fig. 2 is an enlarged fragmentary view in vertical section on line 2—2 of Fig. 1.

Fig. 3 is a view similar to that of Fig. 1 illustrating one of the earlier stages of the working of the concrete mass.

Fig. 4 is a front elevation of a slightly modified form or embodiment of my invention illustrating another method of using, the handles being omitted.

Fig. 5 is a rear elevation of my improved cement concrete working machine as adapted or embodied for the building of trenches shown in operative relation to a form and a mass of concrete.

I have illustrated my improvements as I have embodied the same for the laying of pavements or floors of considerable area and for the building of trenches.

The embodiment shown in Fig. 1 comprises a shoe 1 slightly crowned toward the center. This shoe is of considerable length and of such width that the face of the shoe may be applied to a mass of concrete to be worked and is capable of supporting the machine on the mass, that is, it does not enter the mass materially but is applied to it and supported on the surface thereof.

The side plate 2 is secured at the front edge of the shoe 1 to project upwardly therefrom. This side plate reinforces the shoe and also constitutes a mounting for the vibrating units 3. These vibrating units are electric motors having shafts 4 with unbalancing weights thereon, the units being mounted on the side plate so that the shafts are transverse to the shoe.

In the embodiment shown in Figs. 1 and 2 the shoe and side plate are formed of wood and have metal facings 5. In this embodiment, and in the embodiment shown in Fig. 4, I show a pair of vibrating units arranged toward the end of the shoe. The handles 6 are provided with bar-like grips 7. These handles are upwardly and outwardly curved and formed of springs.

A draft means 8 is attached to the side plate in spaced relation to its lower edge.

In Fig. 1, 9 represents the form and 10 represents the concrete which is being worked.

In use the concrete is placed within the form, preferably roughly dumped therein as shown in Fig. 3, and the machine placed upon the mass with the vibrating units in operation. The concrete mixture is preferably what is known as a dry harsh mixture, that is, there is insufficient moisture to permit the concrete to flow into place or even to be readily tamped. The vibrating units operate at relatively high speed with the result that the character of the concrete mixture is changed so that it readily flows into place and voids are eliminated, even where a very coarse aggregate is employed, and this with no more moisture than is necessary to produce the best results.

After the character of the mass has thus been changed the machine is used in finishing the surface and drawn along by the cable 8, riding upon the upper edges of the forms, thereby serving as a straight-edge and finishing means and further vibrating the mass being worked.

In the modification shown in Fig. 4 the shoe 11 is straight and rests upon the mass of concrete 12 between the forms.

In the embodiment shown in Fig. 5 the shoe is provided with horizontal end portions 13, a horizontal downwardly offset central portion 14 and upwardly diverging intermediate portions 15. The lower edge of the side wall 16 is conformed to the shape of the shoe. This machine is especially designed for the forming of concrete trenches, the concrete being indicated at 17 and the form at 18. The method of using is the same as that described, the shoe being merely adapted to the surface of the finished work.

I have not attempted to illustrate certain other embodiments or adaptations of my improvements as it is believed that this disclosure will enable those skilled in the art to which my invention relates to embody or adapt the same as may be desired.

It is desired to point out that my present improvements are a development of the invention

of my application for Letters Patent filed December 12, 1927, Serial No. 239,568.

Having thus described my invention what I claim as new and desire to secure by Letters Patent is:

5. 1. In a machine for working concrete, the combination of an elongated shoe or screed adapted to be applied directly to and supported by a mass of concrete to be worked or to rest and be manipulated upon the forms for the concrete, and comprising horizontal end portions and a horizontal central portion, said end and central portions being connected by upwardly diverging intermediate portions of substantial length, a side plate fixed to the front edge of said shoe or screed to project upwardly therefrom throughout the length thereof, handles at the ends of said shoe or screed for manually manipulating the same, and a vibrating means comprising a motor having an unbalancing weight carried by said shoe or screed.
10. 2. In a machine for working concrete, the combination of an elongated shoe or screed adapted to be applied directly to and supported by a mass of concrete to be worked or to rest and be manipulated upon the forms for the concrete and comprising horizontal end portions and a horizontal central portion, said end and central portions being connected by upwardly diverging intermediate portions of substantial length, handles attached to said shoe or screed at the ends thereof and projecting outwardly and upwardly therefrom, and vibrating means comprising a motor having an unbalancing weight carried by said shoe or screed.
15. 3. In a machine for working concrete, the combination of an elongated shoe or screed adapted to be applied directly to and supported by a mass of concrete to be worked or to rest upon and be manipulated upon a form for the concrete and having a downwardly offset central portion, a front plate projecting upwardly from said shoe or screed, handles at the ends of said shoe or screed, a draft means, and a vibrating means comprising a motor having an unbalancing weight carried by said shoe.
20. 4. In a machine for working concrete, the combination of an elongated shoe or screed adapted to be applied directly to and supported by a mass of

concrete to be worked or to rest and be reciprocated upon forms for the concrete, a side plate fixed to the front edge of said shoe or screed to project upwardly therefrom throughout the length thereof, handles at the ends of said shoe or screed for manually manipulating the same, a draft means attached to said shoe or screed, and a vibrating means comprising a motor having an unbalancing weight carried by said shoe or screed.

5. 5. In a machine for working concrete, the combination of an elongated shoe or screed adapted to be applied directly to and supported by a mass of concrete to be worked or to rest and be reciprocated upon forms for the concrete, a side plate projecting upwardly from the front edge of said screed or shoe, resilient handles attached to said shoe or screed at the ends thereof and projecting outwardly and upwardly therefrom for manually manipulating the same, and a vibrating means comprising a motor having an unbalancing weight carried by said shoe or screed.

6. 6. In a machine for working concrete, the combination of an elongated shoe or screed adapted to be applied directly to and supported by a mass of concrete to be worked or to rest and be reciprocated upon forms for the concrete, handles attached to said shoe or screed at the ends thereof and projecting outwardly and upwardly therefrom for manually manipulating the same, and a vibrating means comprising a motor having an unbalancing weight carried by said shoe or screed.

7. 7. In a machine for working concrete, the combination of a hand shoe or screed adapted to be applied directly to and supported by a mass of concrete to be worked or to rest and be reciprocated upon forms for the concrete, a side plate projecting upwardly from the front edge of said screed or shoe, and a vibrating means comprising a motor having an unbalancing weight carried by said shoe or screed.

8. 8. In a machine for working concrete, the combination of a hand shoe or screed adapted to be applied directly to and supported by a mass of concrete to be worked or to rest and be reciprocated upon forms for the concrete, and a vibrating means comprising a motor having an unbalancing weight carried by said shoe or screed.

CORWILL JACKSON.
